LEAFLET DISPENSING PULPIT

Gustave Edwin Anderson, La Crosse, Wis.

Application May 23, 1955, Serial No. 36,183

Term of patent 14 years

(Cl. D52—2)

Fig.2

Fig.1

Fig. 1 is a front perspective view of a leaflet dispensing pulpit embodying my new design.

Fig. 2 is a rear perspective view of the same.

The characteristic features of the design reside in the solid line portions.

I claim:

The ornamental design for a leaflet dispensing pulpit, as shown and described.
